CARRIER FOR BOTTLES, CANS, OR
SIMILAR ARTICLES

Marshall I. Williamson, New Haven, Conn., assignor to National Folding Box Company, Inc., New Haven, Conn., a corporation of Connecticut

Application March 30, 1949, Serial No. 84,339

9 Claims. (Cl. 224—45)

1

This invention relates to improvements in carriers made from foldable sheet material, for example, paperboard, for packaging a plurality of bottles, cans, jars, or similar articles as a unit which may easily be carried by the consumer and which, in addition, provides protection for the packaged articles.

In the mass packaging in carriers of goods contained in bottles, cans, and jars, it is essential that the carrier is suited for handling on existing commonly established types of machines. Taking a bottle carrier as a specific example, it is necessary for a carrier, in order to be commercially acceptable, that it can be loaded on the machines which are in established use for loading cases partitioned for individual bottles, so that such cases, as well as cases designed to contain carriers may interchangeably be loaded by the same machine.

A modern bottle carrier should desirably be so constructed that it can be produced and shipped by a paper box manufacturer to the bottler or packer in flat, collapsed condition, that it be suited for erection into hollow carrier form by hand or on relatively simple and inexpensive machinery, and that the carrier after erection will remain in erected position without a tendency to recollapse or distort. This feature is important for the bottler since it facilitates handling of the erected empty carrier and its loading at the bottling plant, and it is important for the consumer, who removes filled bottles and inserts empty ones, either one by one or all at one time, and who should not be expected to re-erect a partially or entirely collapsed carrier.

There are other features which are desirable, for example, the ability of the carrier safely to support a partial or unequal load, for example, two or three bottles on one side of a central handle and none on the other without danger of dumping the bottles when the carrier is lifted up. Various other features and desirable points will be mentioned as the description proceeds.

The invention provides a carrier for bottles, jars, cans and similar articles which meets the specifications heretofore set forth and, in addition, provides numerous other features which make the carrier desirable for the trade.

The various features, objects and advantages of the invention will appear more fully from the detailed description which follows accompanied by drawings showing, for the purpose of illustration, a preferred embodiment of the invention. The invention also consists in certain new and original features of construction and combina-

2

tion of elements hereinafter set forth and claimed.

Although the characteristic features of the invention which are believed to be novel will be particularly pointed out in the claims appended hereto, the invention itself, its objects and advantages, and the manner in which it may be carried out may be better understood by referring to the description which follows taken in connection with the accompanying drawings forming a part of it in which:

Figure 1 is a plan view of a flat blank from which a carrier body embodying the present invention may be made;

15 Figure 2 is a plan view of the blank shown in Figure 1 after an initial folding operation, gluing at this stage being optional;

Figure 3 is a perspective view of the blank shown in Figure 2 in the process of formation 20 of its cellular top structure;

Figure 4 is a perspective view of the formed carrier body viewed upside down to show its bottom construction;

Figure 5 is a plan view of a wire handle for 25 use in connection with the carrier of Figure 4;

Figure 6 is a perspective view of the carrier of Figure 4 turned right side up in the process of insertion of the wire handle;

Figure 7 shows the carrier of Figure 6 with 30 the wire handle fully inserted, the carrier being ready for loading; and

Figure 8 is an end view of the carrier of Figure 7 loaded with bottles.

In the following description and in the claims 35 various details will be identified by specific names for convenience. The names, however, are intended to be as generic in their application as the art will permit. Corresponding reference characters refer to corresponding parts in the several figures of the drawings.

The blank A shown in Figure 1 may be cut and scored in multiple from large rolls or sheets of foldable sheet material, for example, paperboard, on automatic cutting and scoring machines.

45 The blank is shown with its unfinished back side facing the observer.

The several constituent parts of the blank are set apart by fold or crease lines. The blank comprises a center panel 11, a bottom panel 12, an outer side wall panel 13, a top panel 14, a further outer side wall panel 15, a further bottom panel 16 and a further center panel 17. These panels are hingedly interconnected along fold lines 18, 19, 20, 21, 22, and 23. Auxiliary fold lines 24 and 25 may extend across the bottom

panels 12 and 15, respectively, to permit convenient folding of the blank and collapsing of the glued blank into flat condition, as will later appear.

Glue flaps 26 and 27 are hingedly connected to the center panels 11 and 17 along fold lines 28 and 29, respectively. Recesses 30 of somewhat complex configuration are cut into the end of the blank at which the glue flaps 26 lie. All waste material cut from the blank is conveniently removable from the edge of the blank by a stripping operation. The cuts 30 form points 31 on the blank which serve to hold apart the plies of the double thickness webs during assembly of the carrier, as will later appear. There are, in addition, tongues 32 which assist in the assembly and retention of a wire handle in the carrier body. There are further relatively large cut away portions 33 permitting insertion of the bottom portion of the handle, and finally there is a pair of smaller recesses 34 to accommodate the legs of the handle to be combined with the carrier body. All of these functions will become apparent from the description of the assembly of the carrier which follows the description of the blank.

At the other end of the blank a pair of similar recesses 35 is found. These recesses are somewhat simpler in configuration and comprise small cut away portions 34' registering in the assembled carrier with the recesses 34 for guiding the wire handle as will later appear.

Pairs of lock flaps 36 and 37 are cut from the stock of the panels 11, 12, and 16, 17, respectively. These lock flaps are foldable about hinge line 38 and 39 extending substantially at right angles with respect to the transverse fold lines 18 and 23. The hinge lines 39, preferably are spaced apart slightly wider than the hinge lines 38 to facilitate folding of the lock flaps one on top of the other in the assembled carrier. The difference in spacing is preferably equal to twice the thickness of the blank. The lock flaps 36 and 37 have peripheral notches 40 and 41 lying approximately in line with the fold lines 18 and 23. These notches serve to engage the erected center panels in the assembled carrier, as will become apparent from the description dealing with the assembly of the blank.

The center portion of the fold lines 18 and 23 terminates short of the fold lines 38 and 39 and arcuate cuts 42 and 43 extend from the ends of the central portions of the fold lines 18 and 23 to the hinge lines 38 and 39 and form extension tabs 44 and 45 on the bottom panels 12.

The top panel 14 and adjoining portions of the side wall panels 13 and 15 are cut and scored to provide a cellular web structure. Cuts 46, 47, and 48 extend normal to fold lines 20 and 21. These cuts separate the stock into webs 49, 50, 51 and 52, which, after appropriate folding form article receiving cells, as will later appear. The webs are foldable at a plurality of fold lines. These fold lines include diagonal or oblique fold lines, 53, 54, 55, 56, 57 and 58 extending from the ends of the cuts 46, 47 and 48 to the ends of the cuts 46, 47 and 48 to the transverse fold lines 20, preferably at an angle of 45 degrees. Similar diagonal fold lines 59, 60, 61, 62, 63 and 64 extend from the other ends of the cuts 46, 47 and 48 to the transverse fold line 21 and preferably include between one another the same angles as the fold lines 53, 54, 55, 56, 57 and 58.

The webs 49 and 52 constitute terminal webs, since they lie at the outer edges of the blank.

The webs 50 and 51 constitute intermediate webs. These intermediate webs comprise ridge fold lines 65 and 66 to provide for double thickness of the intermediate webs by folding of the stock back upon itself along the ridge fold lines as will later appear.

Apertures 67 and 68 are cut at the center of the web panels 50 and 51 for insertion of a portion of the handle therethrough as will later become apparent.

The assembly of a carrier body from the blank A may proceed as follows:

As a first operation, adhesive *a* is applied to the finished surface of the glue flaps 26 and adhesive may also be applied to the unfinished surface of the flaps 27, the latter application being optional. In the position in which the blank is shown in Figure 1 adhesive would be applied to the under surface of flaps 26 and to the top surface of flaps 27 facing the observer. The adhesive may be conventional glue or may be a heat sealable plastic or other bonding agent.

The blank is then folded about the collapsing creases 24 and 25 to bring the flaps 26 into engagement with the center panel 17 and to bring the flaps 27 into engagement with the center panel 11. In the event glue is used, the bonding is completed at this time. In the event a thermoplastic adhesive is employed the actual bonding of the blank portions may be deferred until after the setting up of the carrier body.

The folded blank is shown in Figure 2. It constitutes a flat collapsed tubular structure *a'* which is ready for setting up as a hollow carrier body. Tubular blanks *A'* may be stored and shipped to the user in flat condition. They require a minimum of space and may be set up into hollow carrier form by performance of a few folding and assembly operations which may be carried out at the plant of the packer or bottler. These assembly operations will now be described.

The blank *A'* is first expanded into hollow shape and, preferably simultaneously, the top panel 14 is converted into a cellular web structure. This may be done in a variety of ways, either manually, semi-automatically, or fully automatically. Figure 3 illustrates two substantially vertically movable plungers 69 and 70 which extend through the apertures formed by the cuts 38 and 39 and engage the top panel along the ridge fold lines 65 and 66. The surface on which the blank rests is preferably provided with three wedge-shaped projections which engage the blank along the cuts 46, 47 and 48 tending to open up the cuts under the pressure of the plungers as shown in Figure 3. The wedges are not shown in the drawing since they would partially obscure the intermediate webs 50 and 51. As the webs 50, 51 and 52 are folded into roof shape as shown in Figure 3 the side walls 13 and 15 automatically begin to erect themselves by reason of the connection of the webs to the side walls along the zig-zag shaped end fold lines 53 to 64.

By hand or by mechanical means the side walls 13 and 15 may now be folded into upright position with respect to the top structure. This causes the webs 49 to 52 to continue folding into the final shape which they assume in the completed body illustrated in Figures 6 and 7.

During the forming and folding of the top and side portions of the carrier body, the center panels 11 and 17 are infolded by bending the blank along the fold lines 28 and 29 which are in substantial coincidence. As the bottom panels 12 and 16 move into final position, the center panels

11 and 17 assume a back-to-back position and the ridge 28 of the center structure enters between the webs 49, 50, 51 and 52.

Referring for a moment to Figure 6, it will be seen that the webs 49 and 52 form straps of single thickness connecting the side walls 13 and 15. These straps extend past the outer edges of the center panels 11, 17. The intermediate webs 50 and 51 forming double thickness straps connecting the side walls 13 and 15 extend through the recesses in the center panels formed by the cuts 30 and 35. It is apparent that the points 31 within the recesses 30 enter between the two thicknesses of the intermediate webs 50 and 51, tending to hold them apart slightly at the bottom edges.

Returning now to Figures 3 and 4, it will be seen that the extension tabs 44 and 45 remain in the plane of the bottom panels 12 and 16. These extension panels overlap, as is apparent from Figure 4 and also from Figure 8 showing the finished carrier body in side view.

The lock flaps 36 and 37 may then be folded upright with respect to the bottom panels 12 and 16 about their respective fold lines 38 and 39. This causes the peripheral notches 40 and 41 to slide along the arcuate cut edges 42 and 43, thus locking the two center panels 11 and 17 together when the lock flaps 36 and 37 assume an upright position with respect to the bottom panels.

In erected position the lock flaps 36 and 37 lie in the same plane as the intermediate webs 50 and 51 and serve, in addition to their function as locking means, as a separator between the bottoms of bottles inserted into the carrier body to prevent glass-to-glass contact between the bottoms. Locking of the center panels 11 and 17 by the lock flaps 36 and 37 completes the setting up operation of the carrier which now appears as shown in Figures 4 and 5 and is ready for installation of a handle.

In the event the glue flaps 26 and 27 were not yet adhesively secured to the respective center panels 17 and 11, as might be the case if a thermoplastic adhesive is used, the bond may now be completed by application of heat and pressure to either side of the top portion of the center walls 11, 17 at, and slightly below, the top fold line 28 of the center wall.

In the completed carrier body A''' each of the webs 49, 50, 51 and 52 is seen to comprise two substantially triangular end portions which are folded back against the side walls 13 and 15, respectively from which they were formed. These end portions lie on the inside of the cells and assist, in combination with the slightly downwardly and inwardly flaring intermediate webs 50 and 51, in guiding bottles, cans, or jars into seating position within the cells, much in the manner of a funnel.

The webs extend at right angles with respect to the side walls 13 and 15. The outermost webs 49 and 52 are of single thickness and the intermediate webs 50 and 51 are of double thickness since the latter webs are formed by folding the stock back upon itself along the ridge fold lines 65 and 66. In assembled position the handle apertures 67 and 68 lie at the points of intersection of the intermediate webs with the center wall 11, 17.

A suitable form of handle for the carrier is shown in Figure 5. The handle 71 comprises a central grip portion 72 from which a pair of

shank portions 73 and 74 extend downwardly. The shank portions 73 and 74 may be offset at 75 and 76 to form an upper pair of shoulders adapted to rest on the ridge 28 of the center wall 11 of the carrier for purpose of limiting the downward movement of the handle. A pair of substantially horizontal lower shoulder portions 77 and 78 extend outwardly. These lower shoulder portions serve to engage the carrier at the fold line 29. End portions 79 and 80 extend from the shoulder portions 77 and 78 first downwardly and then inwardly and upwardly to lie substantially parallel to the shank portions 73 and 74. The ends 81 and 82 of the wire preferably, but not necessarily, extend a slight distance above the upper shoulders 75 and 76. All the portions of the handle preferably lie in the same plane.

The handle 71 is assembled with the carrier body by inserting its lowermost triangular portions to either side of the intermediate webs 50 and 51 into the apertures produced by the cuts 30. For insertion the handle is held slightly at an angle with respect to the center wall 11, 17. The bottom end of the handle slides easily into 20 the space between the center walls 11 and 17 due to the relatively large apertures 33 cut into the center panel 17. The tongues 32 assist in the insertion since they lie approximately in line with the inner upwardly extending end portions 79 and 80 of the handle. The handle is depressed until its upper ends 81 and 82 move underneath the bottom edges of the webs 50 and 51. At this moment the ends 81 and 82 of the handle wire move slightly towards each other by spring action and enter the space between the two plies of the webs 50 and 51 as the handle is being pulled upwardly. The ends 81 and 82 engage the apertures 68 and 67, respectively, in the intermediate webs and thus fix the center wall 11, 17 with respect to the webs 49, 50, 51 and 52.

As it is apparent from Figure 5 that the shanks 73 and 74 of the handle flare slightly downwardly and outwardly. This causes the shanks to be spaced a shorter distance immediately below the upper shoulders 75 and 76 than they are immediately above the lower shoulders 77 and 78. This peculiarity of shape causes the shanks 73 and 74 to engage the recesses 34 in the center portion when the handle is fully depressed, so that, as the handle is pulled up, the shanks are guided between the center walls 11 and 17 by these recesses 34.

The body of the completed carrier is quite rigid 55 and will not recollapse. Resistance to recollapsing is a very desirable feature, since it causes the cells of the carrier to remain properly squared at all times without external restraint.

The dimensions of the handle 71 are so selected that the handle can be depressed below the tops of the bottles. This is illustrated in Figures 7 and 8. In Figure 7 the handle is shown in solid lines in extended position and in dash-dot lines in depressed position. In Figure 8 the handle is 60 shown in solid lines in depressed position and in dash-dot lines in extended position. The purpose of the movement of the handle is to permit the handle to assume a position in which it will not interfere with the stacking of loaded carriers, one 65 on top of the other. It is a practice customary in the beverage industry to stack the carriers so that the bottom of the top-most carrier rests on the tops of the bottles of the carrier underneath.

It is easily apparent that the carrier shown in 70 Figure 7 has great rigidity and strength and that

it will remain properly squared once it is set up. Its construction permits safe carrying of uneven loads. For example, three bottles or less may be carried on one side and none on the other without danger of distortion of the carrier and resultant dumping of the bottles. Shifting of the side walls 13 and 15 with their connecting webs 49, 50, 51 and 52 relatively to the center wall 11, 17 is prevented by the engagement of the handle and portions with the apertures 67 and 68 in the webs 50 and 51.

Referring now to Figure 8, it is seen that the carrier body engages the bottles underneath the neck portion of the bottles, approximately at the area of greatest diameter, whereby the bottles of adjacent carriers, as well as the bottles within each carrier, are protected against glass-to-glass contact. The center wall 11, 17 spaces the two rows of bottles from each other. The webs 50 and 51 at the top and the lock flaps 36 and 37 at the bottom separate the bottles within each row.

Experience has indicated the desirability of making the center wall 11, 17 slightly taller than the side walls 13 and 15. Also it is advantageous to make the top structure somewhat narrower than the combined widths of the bottom panels 12, 16. This inequality in the dimensions of the panels requires the present of the auxiliary collapsing creases 24 and 25, since obviously the tubular blank could not be folded flat with creases 28 and 29 in register if the collapsing creases 24 and 25 were absent.

When bottles, jars, or cans are loaded into the carrier the bottom creases 22 and 19 are broken automatically, since the distance between the fold lines 24 and 18 as well as the distance between the fold lines 25 and 23 is not sufficient to accommodate the bottoms of the bottles. The bottles, therefore, automatically cause the blank to crease at the bottom fold lines 19 and 22 when the bottles are dropped into the carrier.

When the carrier is lifted up by the handle its center wall 11, 17 moves slightly upwardly until the bottom edges of the intermediate webs 50 and 51 come to rest in the bottoms of the cut away portions 30 and 35. Referring briefly to Figure 1 the apex 83 of the cut 35 and the two apexes 84 to either side of the points 31 provide support for the lower edges of the intermediate webs 50 and 51. Since the intermediate webs extend in a substantially vertical plane and are of substantial width they act as supporting beams for the outer side walls 13 and 15 and aid in supporting a portion of the load carried by the outer side walls.

In order to provide for greater strength at the point where the webs meet the side walls it is preferable to score the board by a single continuous curved scoring rule at the points where the fold lines 54, 55, 56, 57 meet the fold line 20 and at the points where the fold lines 60, 61, 62 and 63 meet the fold line 21. This causes the board to curve at a rounded peak rather than to break at a point, whereby the strength of the carrier at the junction of the webs with the side walls is materially increased. The rounded scores produced by the curved scoring knives are indicated in Figure 1 at 85, 86, 87 and 88.

The invention thus provides a sturdy and efficient carrier for bottles, cans, jars and other forms of merchandise. The carrier is attractive and requires a minimum of stock. Its folding and setting up operations are relatively simple and its strength is great, so that it will serve a number of round trips between the bottling plant and the

consumer. The carrier is very resistant to distortion and lends itself admirably to automatic loading on established types of loading machinery now in use for loading partitioned wooden and metal cases.

What is claimed is:

1. A carrier for a plurality of bottles, cans, or similar articles arranged in two rows, the carrier consisting of foldable sheet material creased along fold lines setting apart the several constituent parts of the carrier, the carrier comprising, a pair of outer side wall panels; a center partition panel; a bottom connected to said side wall panels and said partition panel; and a cellular top structure dividing the space between the partition panel and the side wall panels into individual article receiving cells, said top structure comprising webs integral with said side wall panels and extending at substantially right angles to the side wall panels from one side wall panel to the other, and transverse to, said partition, said webs hingedly extending from said side wall panels along diagonal fold lines, the end portions of the webs being folded back upon said side wall panels along said diagonal fold lines, said top structure including terminal webs lying at the ends of the structure and intermediate webs lying between the terminal webs, the intermediate webs being of double thickness, the two thicknesses being folded back-to-back about a crease line forming the ridge of the web.
2. A cellular carton for a plurality of bottles, cans, or other articles arranged in two rows, the carton consisting of foldable sheet material creased along fold lines setting apart the several constituent parts of the carton, the carton comprising, a pair of outer side wall panels; a pair of center panels lying back-to-back and forming a two-ply partition between the side wall panels; a pair of bottom panels hingedly extending from said side wall panels and from said center panels, respectively; and a cellular top structure dividing the space to either side of the center panels into individual article receiving cells, said top structure comprising webs integral with said side wall panels and extending at substantially right angles to the side wall panels from one side wall panel to the other and transverse to, and across, said center panels, said webs extending from said side wall panels along fold lines, the endmost webs being of single-ply thickness, the intermediate webs being of double-ply thickness, all webs being of a length substantially equal to the distance between said side wall panels, whereby the same webs form cells on either side of said partition, the webs of double thickness being formed of stock folded back-to-back about a crease line forming the ridge of the double thickness webs.
3. A cellular carton for a plurality of bottles, cans, or other articles arranged in two rows, the carton consisting of foldable sheet material creased along fold lines setting apart the several constituent parts of the carton, the carton comprising, a pair of outer side wall panels; a pair of center panels lying back-to-back and forming a two-ply partition between the side wall panels; a pair of bottom panels hingedly extending from said side wall panels and from said center panels, respectively; and a cellular top structure dividing the space to either side of the center panels into individual article receiving cells, said top structure comprising webs integral with said side wall panels and extending at substantially right angles to the side wall panels from

one side wall panel to the other and transverse to, and across, said center panels, said webs extending from said side wall panels along fold lines, the endmost webs being of single-ply thickness, the intermediate webs being of double-ply thickness, all webs being of a length substantially equal to the distance between said side wall panels, whereby the same webs form cells on either side of said partition, the webs of double thickness being formed of stock folded back-to-back about a crease line forming the ridge of the double thickness webs, said two-ply partition having notches extending into it from its top edge through which notches said intermediate webs extend.

4. A carrier for bottles, cans, or similar articles arranged in two rows, the carrier consisting of a single blank of foldable sheet material creased along fold lines setting apart the several constituent parts of the carrier, the ends of the blank being attached together so that the blank is of tubular construction, the constituent parts of the carrier comprising a pair of outer side wall panels; a pair of center panels folded back-to-back about a top fold line, said center panels forming a partition between the side wall panels; a pair of bottom panels hingedly connected to said side wall panels and said center panels, respectively; and a cellular top structure dividing the spaced to either side of the center panels into individual article receiving cells, said top structure comprising webs integral with said side wall panels and extending at substantially right angles to the side wall panels from one side wall panel to the other and transverse to, and across, said center panels, said webs extending from said side wall panels along diagonal fold lines, the end portions of the webs being folded back upon said side wall panels along said diagonal fold lines, said webs having a central portion intermediate said end portions, the central portion being of a length substantially equal to the distance between said side wall panels, whereby the same webs form cells on either side of said partition, said center panels having notches extending into them from the top fold line in line with certain of said webs, said certain webs extending through said notches.

5. A carrier as set forth in claim 4 in which the blank is provided with terminal glue flaps hingedly extending from one center panel along said top fold line, foldable over and adhesively securable to the other center panel.

6. A carrier for bottles, cans, or similar articles arranged in two rows, the carrier consisting of a single blank of foldable sheet material creased along fold lines setting apart the several constituent parts of the carrier, the ends of the blank is of tubular construction, the constituent parts of the carrier comprising a pair of outer side wall panels; a pair of center panels folded back-to-back about a top fold line, said center panels forming a partition between the side wall panels; a pair of bottom panels hingedly connected to said side wall panels and said center panels, respectively; a cellular top structure dividing the space to either side of the center panels into individual article receiving cells, said top structure comprising webs integral with said side wall panels and extending at substantially right angles to the side wall panels from one side wall panel to the other and transverse to, and across, said center panels, said webs extending from said side wall panels along diagonal fold lines,

the end portions of the webs being folded back upon said side wall panels along said diagonal fold lines, said webs having a central portion intermediate said end portions, the central portion being of a length substantially equal to the distance between said side wall panels, whereby the same webs form cells on either side of said partition, said webs including terminal webs lying at the ends of the structure and intermediate webs lying between the terminal webs, the intermediate webs being of double thickness, the two thicknesses being folded back about a crease line forming the ridge of the web, said center panels having notches extending into them from the top fold line in line with said intermediate webs, said intermediate webs extending through said notches, certain of said intermediate webs having handle engaging apertures in the ridge at the point of intersection with said center panel; and a wire handle comprising a central handle portion from which two legs depend, the legs including substantially horizontal shoulder portions supporting the carrier at the intermediate webs and upwardly extending end portions extending through said ridge apertures and centering said center panels with respect to said outer side walls.

7. A carrier for bottles, cans, or similar articles arranged in two rows, the carrier consisting of a single blank of foldable sheet material creased along fold lines setting apart the several constituent parts of the carrier, the constituent parts of the carrier comprising a pair of outer side wall panels; a pair of center panels folded back-to-back about a top fold line, said center panels forming a partition between the side wall panels; a pair of bottom panels hingedly connected to said side wall panels and said center panels, respectively along inner bottom fold lines, a lock flap being cut out from the stock of at least one bottom panel and the center panel integral therewith, said lock flap being hingedly connected to the remainder of said last named center panel and of said last named bottom panel along a fold line substantially normal to said bottom fold lines, said lock flap having a notch in its outer edge adapted to engage the two thicknesses of the center panels within it to lock said center panel together when said lock flap is folded upright with respect to the bottom panels; and a cellular top structure dividing the space to either side of the center panels into individual article receiving cells, said top structure comprising webs integral with said side wall panels and extending at substantially right angles to the side wall panels from one side wall panel to the other and transverse to, and across, said center panels, said webs extending from said side wall panels along diagonal fold lines, the end portions of the webs being folded back upon said side wall panels along said diagonal fold lines, said webs having a central portion intermediate said end portions, the central portion being of a length substantially equal to the distance between said side wall panels, whereby the same webs form cells on either side of said partition.

8. A bottle carrier blank cut and creased to provide a plurality of panels set apart by parallel crease lines and comprising from one end of the blank to the other, a center panel, a bottom panel, a side wall panel, a top panel, a further side panel, a further bottom panel, and a further center panel, the width of the top panel measured between its bordering crease lines being substantially equal to the added width of the bottom

11

panels, the top panel having a plurality of parallel cuts through it normal to said crease lines to provide web forming strips, said cuts extending beyond the body of the top panel into the body of the adjoining side wall panels, said side wall panels having oblique fold lines extending from the ends of the cuts to the crease lines bordering said top panel.

9. A bottle carrier blank as set forth in claim 8 in which, in addition terminal securing flaps are ¹⁰prointegral with, and hingedly connected to, the ends of the center panels about fold lines parallel to said crease lines, said securing flaps being at-

12

tachable to the center panels with which they are not integral to provide a tubular blank structure.
